STOKER MECHANISM

Edwin Archer Turner, New York, N. Y., assignor, by mesne assignments, to The Standard Stoker Company, Inc., New York, N. Y., a corporation of Delaware

Application July 21, 1934, Serial No. 736,316

3 Claims. (Cl. 110—101)

This invention relates to stoker mechanism and more particularly to fuel distributors or other terminal parts of stokers.

The main object of the invention is the provision of improved means for cooling the fuel distributor plate of the stoker exposed to the intense heat of the fire of the boiler furnace.

Another object of the invention is to employ the pressure fluid of the fuel propelling blasts as a cooling medium for the fuel distributor plate of the stoker and to cause this fluid to pass through the fuel distributor plate before entering the pressure regulating valves for the propelling blasts.

15 A further object of the invention is the provision of means in the pressure fluid supply system of the stoker for first passing the pressure fluid for the propelling blasts into the fuel distributor plate of the stoker and thence to the pressure regulating valves for the propelling blasts or for cutting out of operation the flow of fluid to the fuel distributor plate and passing the fluid directly to the aforesaid regulating valves.

25 Other objects and advantages of the invention will be apparent from the following description taken in connection with the accompanying drawing, in which,

Fig. 1 is a central vertical longitudinal sectional view through the rear portion of a boiler furnace with the device of the invention similarly shown;

Fig. 2 is a sectional view taken on the line 2—2 of Fig. 1; and

35 Fig. 3 is a plan view of the chambered fuel distributor of the invention.

On the drawing, 10 illustrates a boiler furnace having the upstanding wall 11 which embodies the firing opening 12 through the lower portion 40 of which fuel is delivered to the furnace by the stoker 13 and above which stoker fuel may be fed manually through the firing opening, the upper part of which is covered by the usual form of firedoor 14. Only that portion of the stoker 45 13 is shown which is necessary to illustrate the present invention.

The stoker 13 includes the discharge conduit 15, the mouth portion 16 of which opens forwardly into the firing opening 12. A distributor 50 plate or terminal part 17 of the stoker is positioned in the mouth portion 16 where it is removably secured to the conduit by spaced tap bolts 18. The plate or terminal part 17 extends forwardly through the firing opening into the 55 furnace 10 and because of its location it is ex-

posed to the flame of the fire or to the intense heat thereof. This plate may carry the abutment ribs 19 or other equivalent means for cooperating with the pressure fluid fuel propelling blasts discharging from the rearwardly disposed 5 jet or distributor head 20 to spread the fuel over the firebed.

The distributor head 20 is mounted in the mouth portion 16 back of the distributor plate 17 and is secured in this position by the cap screws 10 21. Jet openings 22 in the front face of the head 20 in a position to direct pressure fluid over the plate 17 communicate with a plurality of separated chambers 23. Each chamber is open at its bottom end to receive one of the supply 15 pipes 24 leading from a manifold 25 disposed on the wall 11 at one side of the stoker conduit. The chamber 26 of the manifold communicates with the supply pipes 24 and it receives pressure fluid from the pipe 27. A regulating valve such 20 as an ordinary globe or needle valve 28 is placed in each supply line 24 between the manifold and the distributor head to control the pressure of the fluid propelling blasts.

Thus far the construction described is well 25 known in the art, particularly as embodied in the "Standard BK Type Stoker". The novelty of the present invention is the provision with the construction described or the like of means for employing the pressure fluid for the fuel propelling blasts as a cooling medium for the distributor plate of the stoker in a manner not to interfere with the operation and control of the propelling blasts. This means now will be described.

35 Pressure fluid from a suitable source of supply is conducted by the main supply line 30 through the globe valve 31 to the two-way valve 32. The supply pipe 27 of the manifold opens into one side of the two-way valve 32 and at the opposite 40 side a supply line 33 leads from the aforesaid valve to the distributor plate 17 where it opens into an enclosed chamber 17a formed at the under side of the plate constituting in effect a chambered jacket. The chamber 17a is divided 45 by the ribs 17b into a plurality of smaller chambers 17c which communicate at opposite ends through the apertures as at 17d in the ribs. At the same side of the plate but at the end thereof opposite the opening for the intake line 33, a pipe 50 34 leads from the chamber of the plate to the two-way valve 32 into which it opens opposite the main supply line 30.

As best shown in Fig. 2, the valve member 32a of the two-way valve can be set by the handle 55

32b to divert the pressure fluid from the main supply line 30 either to the supply line 27 or to the supply line 33. Any suitable form of two-way valve may be used that will control the pressure fluid as described.

In normal operation of the stoker mechanism, the fuel advances upwardly in the discharge conduit 15 and forwardly into the mouth portion 16 where it rolls or falls over the distributor head 20 onto the distributor plate 17 within the zone of action of the pressure fluid propelling blasts discharging from the jet openings 22. The pressure fluid to the jet openings is first brought from a source of supply through the main supply line 30 and its valve 31 to the two-way valve 32. There the pressure fluid is directed by the setting of the valve member 32a into the pipe line 33 from which it flows into the chamber 17a of the distributor plate. Within this chamber the pressure fluid flows longitudinally back and forth through the smaller connecting chambers 17c until it reaches the outlet line 34 through which it flows back into the two-way valve 32 on the other side of the valve member 32a which directs it into the supply pipe 27 and thence to the chamber 26 of the manifold 25.

From the manifold the pressure fluid flows into the pipes 24 which conduct the pressure fluid to the chambers of the distributor head 20. The valves 28 in the pipes 24 control the pressure of the blasts discharging through the jet openings and may be regulated independently of one another to discharge propelling blasts of different forces.

35 Should the exposed portion of the chambered plate 17 eventually crack or burn through, causing a flow of pressure fluid into the furnace, the flow of fluid to the chambered plate can be cut off and the fluid fed directly to the manifold by 40 changing the setting of the valve member 32a so that it will cause the pressure fluid to pass directly from the main supply line 30 to the manifold connection line 27.

Preferably, I contemplate utilizing saturated steam as the pressure fluid. The saturated steam passing through the chambered plate 17 will absorb heat and serve to cool the plate; and, in effect, the chambered plate will function somewhat as a super-heater for the saturated steam 50 tending to decrease the water content thereof and thus minimize so-called water-cutting of the jet openings 22.

I claim:

1. In a stoker mechanism for a boiler furnace, 55 a hollow distributor plate adapted to extend into the furnace, a distributor head having passages

therethrough arranged to discharge fuel propelling blasts across the upper surface of the distributor plate, a manifold having a pressure fluid supply chamber, supply lines establishing communication between said chamber and the passages in the distributor head, regulating valves in said supply lines adapted to control said blasts, and means for supplying pressure fluid into said hollow distributor plate and thence into the supply chamber of said manifold, said means including a valve mechanism operable to cut off the supply of pressure fluid to said hollow distributor plate and to divert said fluid directly to said supply chamber of the manifold. 5

2. A stoker mechanism for supplying fuel to a boiler furnace comprising a distributor table located at the furnace end of said mechanism and being exposed to the heat of the furnace, said distributor table having a fuel supporting top wall and means providing a chamber beneath 20 said top wall, a jet head having a passage therethrough arranged to discharge a blast of fluid under pressure across the top wall of said distributor plate for projecting fuel over the furnace firebed, and means leading from a source of supply for supplying pressure fluid directly into said chamber and thence into the passage in said jet head, said last named means including valve mechanism operable to cut off the supply of pressure fluid to said chamber and to divert such 30 fluid from the source of supply to the passage in said jet head. 25

3. A stoker mechanism for supplying fuel to a boiler furnace comprising a distributor table located at the furnace end of said mechanism and being exposed to the heat of the furnace, said distributor table having a fuel supporting top wall and means providing a chamber beneath 35 said top wall, a jet head having a passage therethrough arranged to discharge a blast of fluid under pressure across the top wall of said distributor table for projecting fuel over the furnace firebed, a manifold having a pressure fluid supply chamber, a supply line establishing communication between the second named chamber and the passage in said jet head, a regulating valve in said supply line adapted to control the flow of fluid from the second named chamber to the passage in said jet head, and means leading from a source of supply for supplying pressure fluid 40 directly into the first named chamber and thence into the second named chamber, said means including valve mechanism operable to cut off the supply of pressure fluid to the first named chamber and divert such to the second named chamber. 45 50

EDWIN ARCHER TURNER. 55
